TEXTILE SPOOL

Rawson Atwood, New York, N. Y., assignor to
 Decorated Metal Manufacturing Company, Inc.,
 Brooklyn, N. Y., a corporation of New York

Application September 16, 1941, Serial No. 411,002

7 Claims. (Cl. 242—120)

This invention relates to improvements in textile spools.

It is an object of the invention to provide a textile spool or winding tube suited for receiving textile fibres from spinning machines and which is of low weight and cost, permitting it to be used for shipping packages, where desired. Many features of the invention are applicable also to driven textile spools and to cops, tubes, bobbins and textile spools in general.

It is a further object of the invention to provide a composite spool structure fabricated of sheet metal and cardboard parts and having characteristics of strength, accuracy and durability heretofore not obtainable with such methods of fabrication.

With these and other objects which will appear in the following description in mind, the invention consists in the combinations and arrangements of parts and details of construction which will now first be fully described in connection with the accompanying drawing and then pointed out more particularly in the appended claims.

In the drawing:

Fig. 1 is an exploded view in central longitudinal section showing the parts going to make up a flangeless pirn or winding tube embodying the invention in a preferred form;

Fig. 2 is a side view, partly in central longitudinal section, showing the completed structure made up of the parts in Fig. 1;

Fig. 3 is an end view showing the drive end of the pirn;

Fig. 4 is an end view showing the opposite or winding end of the pirn;

Figs. 5 and 6 are transverse sections taken respectively on the lines 5 and 6 of Fig. 1; and

Fig. 7 is a fragmentary side view, partly in central longitudinal section, showing a modified type of construction for the winding end.

The barrel of the pirn includes an outer tubular barrel 1, preferably of pasteboard or similarly deformable material and which may be impregnated with a phenolic resin or the like so as to harden it and improve its surface characteristics. Within outer barrel 1 are positioned outer and inner split metal tubes 2 and 3 respectively, the splits in which are preferably positioned opposite each other where very accurate balance is required. These split metal tubes are urged outwardly against the inner surface of outer barrel 1 by transverse annular or cup-shaped braces 4 which are driven into tube 3 so as to force the tubes 2 and 3 outwardly against the

outer barrel 1 with sufficient pressure to compel the outer barrel 1 to conform to the straight cylindrical contour of outer tube 2.

The drive end assembly includes a metallic cap member 5 which may be drawn from a single piece of metal and which has a central aperture 6 forming a spindle bearing. The cap member 5 includes also a cylindrical portion 7 concentric with the aperture 6 and adapted to be driven into tube 3. A plug 8 of wood or any other desired material provides means for engaging the whorl of a spinning machine, being formed with a central opening 9 to accommodate the spindle and a transverse slot 10 to engage the lugs of the whorl. The central opening 9 should be larger in diameter than the spindle and the spindle bearing 6 so as not to interfere with proper engagement and centering of the spindle by the spindle bearing 6. The plug 8, where made of wood, may be provided with any of the usual metallic facings or protectors at points of wear. Plug 8 is formed with a cylindrical portion 11 which fits into cylindrical portion 7 of the cap member and is fastened therein as by means of 10 inwardly punched portions 12 of the cap member metal. Below this cylindrical portion the plug is provided with an annular shoulder 13 which engages against a corresponding flat portion 14 of the cap member 5. Cap member 5 is provided with a skirt or rim 15 adapted to fit over the end of the barrel as shown in Fig. 2 and to be pressed into the barrel so as to fasten the drive end assembly thereto.

The winding end assembly comprises an upper spindle bearing 16 which includes an aperture 17 to engage a spindle and a body portion 18 concentric therewith and adapted to be driven into tube 3 as shown. It will be noted that this upper bearing construction permits the use of winding tubes or flangeless pirns upon spindles designed for shorter pirns. One connection in which this feature assumes importance is in the use of a flangeless pirn as a substitute for a single flanged pirn. In such use the fibre will be wound upon the barrel in the form of a cylinder with sloping or frusto-conical ends and over a length such that the fiber does not touch the skirt 15 at the drive end or reach the end of the barrel at the winding end. Under such circumstances, it is necessary to provide a longer structure if the same amount of material is to be carried as can be wound upon a flanged pirn.

A bearing surface for the textile fibre is provided in the form of a washer 19 surrounding outer split metal tube 3 and abutting against

the winding end of outer barrel 1. This furnishes a smooth surface for the thread to pass over and can be ground down or polished as required to eliminate nicks or other irregularities. Washer 19 is provided with an annular recess 20 receiving an angle shaped ring 21 by means of which the washer is held upon the barrel, the end 22 of outer split metal tube 2 being turned over, as shown, for that purpose. The upper end assembly is completed by a cap member 23 provided with an aperture 24 to accommodate a spindle, but which should be of greater diameter than aperture 17 so as not to engage the spindle, and with a cylindrical portion 25 adapted to be driven into inner split metal tube 3. The rim 27 of this cap member is turned over the end 22 of tube 2 so as to cover the same and to fasten cap member 23 to the pim. This cap member furnishes a place for the insertion of identifying cards and may be provided with inwardly extending nibs 28 for holding the same. The cap member may abut against member 16 as shown in Fig. 2 for the purpose of holding the bearing 17 in place against any upward thrust of a spindle during placing of the pim thereon.

The structure of the invention may be assembled as follows: the inner and outer split metal tubes 2 and 3 are placed within outer barrel 1 and the expanders 4 driven in as shown in Fig. 1. Washer 19 and ring 21 are now placed in position and the upper end 22 turned over as described. Insertion of upper bearing member 16 completes the assembly so far as shown in Fig. 1. The insertion of cap member 23 and the turning over of its rim 27 completes the assembly of the winding end and the insertion of the drive end assembly and turning inward of skirt 15 completes the assembly of the drive end.

As will be apparent, the construction of the invention involves the use only of simple and easily constructed parts which may be assembled without difficulty or the employment of precision methods. Nevertheless, dynamic balance and concentricity are insured by the centering of the bearing and driving members with relation to the inside of the inner tube, as described. These features, together with the great barrel strength provided, are of particular importance with synthetic fibres such as rayon, "Nylon" or the like, and insure satisfactory operation in winding at speeds of about 8000 R. P. M.

In certain cases where washer 19 is not required, a modified upper end construction as shown in Fig. 7 may be employed. In this case both split metal tubes terminate with outer barrel 1 or slightly short of the end thereof and a cap member 29 is inserted therein. The rim 30 of this cap member is turned into the end of outer barrel 1 as shown in Fig. 7. The cap member 29 being otherwise similar to cap member 23 previously described requires no further description.

It will be apparent that many features of the present invention and principally those relating to the barrel reinforcement are applicable to single or double flanged constructions, as well as to the unflanged construction shown.

My copending application Serial No. 411,001, filed September 16, 1941, for improvements in Textile spools discloses a flanged pim construction having features in common with the construction of the present application as to the barrel reinforcement and centering of spindle bearings with relation thereto. As to such common features, the claims of the present application are directed to constructions of either flanged or flangless type and to constructions of the flangless type, while the claims of my copending application, Serial No. 411,001 are directed to flanged constructions.

What is claimed is:

1. In a textile spool, and in combination, a tubular outer barrel, and a reinforcement assembly within said barrel, the said assembly comprising inner and outer split metal tubes and means within said inner split metal tube for expanding said tubes against the inner surface of said outer barrel.
2. A textile spool according to claim 1, in which said outer barrel is composed of pasteboard or similarly deformable material and the said outer split metal tube is expanded against the inner surface of said outer barrel with sufficient pressure to force said outer barrel to conform to the shape of said outer split metal tube.
3. In a textile spool, and in combination, a tubular outer barrel of pasteboard or similarly deformable material, and a reinforcement assembly within said barrel, the said assembly comprising inner and outer split metal tubes and a plurality of transverse annular braces positioned within said inner split metal tube for expanding said tubes against the inner surface of said outer barrel.
4. A textile spool according to claim 3, in which the said transverse annular braces include members having centered apertures for engaging a spindle.
5. In a flangeless textile spool, and in combination, a tubular barrel and a drive end therefor, the said drive end comprising a hollow metallic member fitting within the said tubular barrel and having a centered aperture for engaging a spindle and a second member attached to said metallic member, said second member comprising a plug fitting within said hollow metallic member and having a central bore larger than a spindle base for accommodating a spindle base and provided with a transverse slot for engaging the driving lugs of a whorl.
6. In a flangeless textile spool, and in combination, a tubular barrel and a drive end therefor, the said drive end comprising a hollow metallic member fitting within the said tubular barrel and having a centered aperture for engaging a spindle, and a plug fitting within said hollow member, having a central aperture larger than a spindle base and provided with means for engaging the driving lugs of a whorl.
7. A flangeless textile spool according to claim 6, in which the said hollow member comprises also a rim portion surrounding said tubular barrel and fastened thereto.

RAWSON ATWOOD.
